UNITED STATES PATENT OFFICE.

BENJAMIN WOLHAUPTER, OF NEW YORK, N. Y., ASSIGNOR TO THE RAIL JOINT COMPANY, OF NEW YORK, N. Y., A CORPORATION OF NEW YORK.

INSULATED RAIL-JOINT.

No. 868,517.

Specification of Letters Patent.

Patented Oct. 15, 1907.

Application filed November 8, 1906. Serial No. 342,523.

To all whom it may concern:

Be it known that I, BENJAMIN WOLHAUPTER, a citizen of the United States, residing at New York city, in the county of New York and State of New York, have 5 invented certain new and useful Improvements in Insulated Rail-Joints, of which the following is a specification.

This invention relates to rail joints of the insulated type, and has special reference to certain novel and 10 practical improvements in joints of this character wherein an effective support and reinforcing of the service rail ends is secured, while at the same time preserving a thorough and complete insulation of the joint parts.

15 To this end the invention primarily has in view an insulated joint structure wherein each rail end has a supporting base independent of that for the other rail end, while at the same time the individual support for each rail end is reinforced throughout the entire 20 length of the joint. In this connection the invention contemplates an individual and independent metal base support for each rail end which may be so arranged as to be carried upon two ties.

A further object of the invention is to provide a construction which preserves a complete insulation of the 25 entire joint, while at the same time providing a direct metal bearing or base support for the rail ends so that in the principal forms of the invention there is no insulation which is required to carry the load or weight 30 of the passing trains.

The essential features of the invention are necessarily susceptible to a wide range of structural modification and also capable of application to many varieties of side joint plates, chairs, angle bars, or splice 35 bars, without departing from the scope of the invention, but for illustrative purposes there are shown in the drawings certain practical embodiments of the invention.

In these drawings: Figure 1 is a sectional perspective 40 view of a rail joint embodying the present invention. Fig. 2 is a detail perspective view showing the matching relation of the joint shoes illustrated in Fig. 1. Fig. 3 is a top plan view of the matching shoes, omitting the insulation and bolts and indicating by dotted 45 lines the separate rail ends. Fig. 4 is a sectional view showing another form of rail joint embodying the invention. Figs. 5 and 6 are separated perspective views respectively of the opposite joint shoes, and showing a modification in the formation of the upright members 50 to present flat, vertical abutments for the heads and nuts of the bolts. Fig. 7 is a sectional perspective view illustrating another modified construction of joint embodying the improvements claimed herein. Fig. 8 is a perspective view of the joint shoes shown in the 55 modification of Fig. 7, and illustrating in dotted lines

the insulating end post arrangement. Fig. 9 is a top plan view of the parts shown in Fig. 8, omitting the upper portion of the end post.

Like references designate corresponding parts in the several figures of the drawings.

A distinctive feature of the present invention is that of providing a divided rail-supporting base comprising separate complementary base plates, each of which constitutes an independent metal supporting base for one rail end. This plan of construction possesses many 65 structural advantages largely on account of each rail end having a separate base plate so designed and so arranged with reference to the track ties that the rail bases rest directly upon individual metal base supports without the interposition of base insulation of 70 any character. It is therefore the purpose of the present invention to embody the divided or two-part base idea in structures meeting all of the necessary structural and engineering requirements of a strong, durable, and effective insulated rail joint.

Referring to that exemplification of the invention shown in Fig. 1 of the drawings, the rail joint proper includes the service rail ends 1 and 2, the oppositely arranged complementary joint shoes 3 and 4, and the wooden or equivalent filler blocks 5 and 6, respectively 80 interposed between the joint shoes 3 and 4, and the adjacent sides of the rails. The joint shoes are arranged respectively at opposite sides of the rails and each consists of an angle plate having an upright member 7, and a horizontal flat base plate 8 projecting inwardly from the lower edge of the upright member 7 so as to lie beneath a rail base. Though different designs of joint shoes may be employed, yet each shoe 3 and 4 preferably consists of an integral body; in which the upright member or girder 7 is integral with the base 90 member or base plate 8. At the outer corner of the shoe, the same may be formed with a continuous reinforce and spiking flange 9 extending the full length of the shoe. Also, the upright member of each shoe may be arranged at right angles to the base plate member 8 95 so as to lie in a perpendicular plane and be clamped directly against the outer shoulder faces 10 of the filler blocks 5 and 6, whose inner sides or faces conform to and fit against the sides of the rails beneath the rail heads in the manner common to the filler blocks in the well known Weber types of rail joints. The said upright member 7 may be properly and broadly termed a side joint plate, which plate, for the purposes of the present application, and other co-pending applications, will be understood to be that plate receiving the 100 joint bolts and also carrying a half-length base member or base plate 8.

In the form of joint being described, the distance between the side plates 7 of the opposite shoes 3 and 4 is illustrated as being greater than the width of the rail 110

base, and also each base plate 8 is shown of greater width than the rail base resting thereon. Furthermore, the base plate of each shoe is of a length approximately equaling one-half the full length of the rail joint members so that each base plate receives and supports thereon one rail end, and, in order that the support for both rail ends may be alike, the separate base plates are duplicates in design and arrangement, and are located respectively at opposite sides of the joint between the meeting ends of the rails. In this connection, it will be seen that the opposite shoes 3 and 4 are constructed alike, though one of said shoes, designated by the number 3, has the base plate 8 projected inwardly from one end portion thereof only, while the opposite shoe, designated by the number 4, has its base plate projected inwardly from the correspondingly opposite end portion thereof.

The opposite complementary shoes 3 and 4 are shown arranged with an intervening space or gap between the inner adjacent edges of the separate base plates, while the longitudinal edge 11 of each base plate 8 is arranged in parallelism to and spaced from the longitudinal edge 12 of a narrow horizontal girder flange 13 projected inwardly from the lower edge of the side joint plate of the opposite shoe. This flange is the portion of the metal left by the shearing or casting operation along that end portion of the shoe or joint plate which is not provided with a supporting base plate for a rail end, and forms a narrow reinforcing continuation of the base plate 8 of each shoe.

Various insulating expedients may be resorted to. One of these, as shown in Fig. 1 of the drawings, resides in constructing each of the opposite filler blocks 5 and 6 with a pendent insulating lip 14 projected from the bottom side thereof, and lying between the edges 11 and 12 of the opposing base plate and girder flange below the filler. In this construction each filler is only provided with a half-length insulating lip 14 along that portion of the block overlying the interval between a base plate 8 and the flange 13 on the opposite shoe or joint plate.

The end insulation between the adjacent end edges of the separate base plates 8 may be provided for by any suitable or practical form of insulation. The air gap itself, might, under some conditions, provide sufficient insulation, but it is preferable to provide a definite insulation at that point. This may be accomplished by utilizing the insulating end post 15, (between the service rail ends), as the insulating medium, such use of the end post only requiring the base 16 of the end post 15 to be sufficiently wide to drop into the interval between the adjacent end edges of the separate base plates 8. This scheme of insulation is plainly shown in Figs. 8 and 9 of the drawings.

In the assembling and fastening up of the joint parts constituting the structure illustrated in Fig. 1, there are employed the usual series of joint bolts 17, whose heads and nuts are clamped directly upon the side joint plates, while an insulation between the bolts 17 and the rail webs is secured by having the rail bolt holes 18 fitted with elongated insulating sleeves 19 projecting beyond both sides of the rail webs, and held within openings provided in metallic tension straps 20 arranged upon opposite sides of the webs of the rails. To complete this insulation, insulating straps

22 are interposed between the inner faces of the metal tension straps 20 and the adjacent faces of the rail webs. (See Fig. 1).

The form of joint just described is preferably designed for use in connection with a pair of track ties 70 23 arranged respectively at opposite sides of the vertical plane of the joint between the rail ends. With such arrangement, each joint shoe or side joint plate has a support on both ties; thus giving each rail end a base support carried by two ties. 75

In the modification shown in Figs. 4, 5 and 6 the rail joint as an entirety is made up of the same general combination and relation of parts as the joint shown in Fig. 1 of the drawings, with the prominent difference that the opposite joint shoes 24 and 25 of 80 the modified structure are provided with upright side plates 26 set at an inclination to a vertical plane, and which clamp upon the correspondingly inclined outer bearing faces 27 of the wooden filler blocks 28 and 29 interposed between the rails and the said side plates. 85 Like the construction shown in Fig. 2, each of said shoes 24 and 25 is provided along one end portion thereof, with an inwardly projecting horizontal flat base plate 30 adapted to lie beneath and constitute a base support for one of the rail ends, and the separate 90 base plates 30 are arranged in the same horizontal plane in spaced relation with their longitudinal edges disposed opposite and spaced from the longitudinal edges of the narrow girder flanges 31. The elements 30 and 31 occupy the same relation and preserve the 95 same functions as the corresponding elements 8 and 13, previously described.

By reason of the complementary inclined faces of the filler blocks and the inclined side joint plates 26, it will be obvious that when the bolts are tightened, 100 the joint shoes will be drawn or lifted in a vertical direction, thereby drawing the metal base plates 30 into firm contact with the rail bases.

In the modification shown in Fig. 4 of the drawings, the insulating end post 15 may be utilized as the insulating medium between the adjacent inner end edges of the separate base plates 30, while for insulation between each base plate and the opposing girder flange, there may be used an insulating strip 32 clamped upon each flange 31 beneath the wooden filler thereover, and, 110 having its pendent flange portion 33 lying between the elements 30 and 31. Also, the joint bolts 34 may be passed directly through the bolt holes 35 in the rail webs and insulating bushings 36 interposed between the heads and nuts of the bolts and the adjacent sides of the 115 joint plates 26, and having at one side neck or collar extensions 37 projecting into the bolt holes in the said plates. A modification of this construction is suggested in Figs. 5 and 6 of the drawings, wherein the upright members of the shoes are illustrated as being 120 formed along their upper edge portions with reinforce ribs 50 presenting vertical, flat abutment faces 51 for the head and nut parts of the bolts to be drawn against. This obviates the use of bevel washers or the like to provide vertical abutment faces for the bolts. 125

Another modification of the invention is shown in Figs. 7, 8 and 9 of the drawings. This construction of joint is very similar to the one shown in Fig. 1 of the drawings and differs therefrom principally in the particulars of showing a modified arrangement of insula- 130

tion between each base plate, and the opposing girder flange of the opposite shoe, and in the reinforcement of the individual shoes themselves. Hence, similar reference characters are applied to the same joint parts 5 illustrated in the group of figures 7, 8, and 9, and in Fig. 1 of the drawings. Referring to the modified features it will be noted by reference to the said group of figures 7, 8, and 9 of the drawings, that each of the joint shoes 3 and 4 may be provided intermediate their ends with pendent 10 reinforcing girders 39. The girder 39 of each shoe projects below the horizontal plane of the base plate 8 thereof and lies between the two ties upon which the joint is supported. Also, in the construction referred to, the proper insulation between the base plates 8 and the opposing girder flanges 13 is provided for by insulating strips 40, one for each base plate member 8. Each insulating strip 40 is clamped upon the flange of the rail by the wooden filler block thereover, and the pendent portion 41 of the strip lies between the opposing edges 15 of the base flange and the adjacent girder flange 13.

Insulation of the modified type of joint shown in Fig. 7 of the drawings is completed by the end post insulation 15 between the rail ends, as previously referred to, and by the employment of plain insulating bushings or 25 sleeves 42 inserted in the bolt holes of the rail ends.

Various other modifications of joints of the Weber and other types may be obviously utilized in connection with the special improvements herein emphasized, but from the foregoing it is thought that the construction, 30 use, and advantages of the several parts will be readily apparent to those skilled in the art without further description.

I claim:

1. In an insulated rail joint, the service rails, opposite one-piece shoes, each provided with an integrated full length side plate and a short length base plate, the latter supporting one rail end only, and means for insulating one rail from the other.
2. In an insulated rail joint, the service rails, opposite 40 one-piece shoes, each provided with a full length side plate reinforced along its bottom edge throughout, and a short length base plate integrated with the bottom edge of the side plate and affording a support for one rail end only, and means for insulating one rail from the other.
3. In an insulated rail joint, the service rails, and opposite shoes each provided with a full length side plate reinforced at its bottom edge throughout along the outer and inner sides thereof, each shoe also having a short length base plate for supporting one rail end only and formed integral with the side plate, and means for insulating one rail from the other.
4. In an insulated rail joint, the service rails, opposite 50 shoes each having a full length side plate and a short length base plate for one rail end only, and transverse insulation between the base plates.
5. In an insulated rail joint, the service rails, side joint plates each provided with a short length base plate for one rail end, and with a girder flange continued from and narrower than the base plate and projecting inwardly 55 from the side plate, and means for insulating one rail from the other.
6. In an insulated rail joint, the service rails, side joint plates each provided with a base plate for one rail end and with a narrow girder flange continued from the 60 inner end of the base plate, along the inner side of the joint plate, to one end of the latter, and means for insulating one rail from the other.
7. In an insulated rail joint, the service rails, side joint plates each provided with a base plate for one rail 65 end, and with a narrow girder flange continued from the base plate and projecting inwardly from the bottom edge

of the side plate, each base plate lying opposite the said girder flange of the opposite joint plate, and means for insulating one rail from the other.

8. In an insulated rail joint, the service rails, opposite 75 complementary joint shoes each having an individual base plate of shorter length than the shoe, and a narrow girder flange continued from one end of the base plate and projecting inwardly from the bottom edge of the upright member of the shoe, the base plates of the two shoes 80 being arranged in the same horizontal plane in matching relation, and each base plate lying opposite and spaced from the girder flange of the opposite shoe and means for insulating one rail from the other.

9. In an insulated rail joint, the service rails, opposite 85 joint shoes each provided with an integral base plate for one rail end only, the separate base plates being arranged in the same horizontal plane in spaced and matching relation, transverse insulation between the individual base plates, and between each base plate and the opposite shoe, 90 and insulation between the shoes and the rail sides.

10. In an insulated rail joint, the service rails, opposite joint shoes each having an individual base plate for one rail end only, transverse insulation between the separate 95 base plates, and a filler block interposed between each shoe and the rail sides.

11. In an insulated rail joint, the service rails, opposite shoe angles each having an individual base plate for one rail end, wooden filler blocks interposed between the upright members of the shoe angles and the rail sides, insulation interposed between each base plate and the opposite shoe angle, joint bolts passing through the upright members of the shoe angles, the filler blocks, and the rail webs, and insulating elements interposed between the heads and nuts of the bolts and the upright members of the 100 shoe angles.

12. In an insulated rail joint, the service rails, opposite joint shoes each having an integral individual base plate for one rail end only, means for exerting a lifting force upon the shoes by the drawing together of the joint parts, 105 and means for insulating one rail from the other.

13. In an insulated rail joint, the service rails, opposite joint shoes each having an integral individual base plate for one rail end only, and an inclined upright member, 110 filler blocks arranged between the shoe uprights and the rail sides and having inclined bearing faces engaged by said shoe uprights, and means for insulating one rail from the other.

14. In an insulated rail joint, the service rails, side joint plates each carrying a rail supporting base for one 115 rail end only, and an insulating end post for the rail ends arranged to insulate the separate base plates.

15. In an insulated rail joint, the service rails, side joint plates each carrying a rail supporting base for one rail end only, and an insulating end post for the rail ends 120 arranged to insulate the adjacent ends of the separate base plates.

16. In an insulated rail joint, the service rails, side joint plates each carrying a rail supporting base for one rail end only, and an insulating end post for said rail 125 ends, said insulating end post projecting below the rail bases.

17. In an insulated rail joint, the service rails, side joint plates each carrying a rail supporting base for one rail end only, and an insulating end post for the rail 130 ends, said insulating end post projecting below the rail bases into the gap between the adjacent ends of the separate base plates.

18. In an insulated rail joint, the service rails, a separate rail supporting base for each rail end, and an insulating end post for said rail ends, said insulating end post projecting below the rail bases and between said 135 separate supporting bases.

In testimony whereof I hereunto affix my signature in the presence of two witnesses.

BENJAMIN WOLHAUPTER.
